UNITED STATES PATENT OFFICE.

GEORGE R. STEINHAUSER, OF ST. LOUIS, MISSOURI.

DESIGN FOR A LAMP.

SPECIFICATION forming part of Design No. 26,825, dated March 30, 1897.

Application filed February 1, 1897. Serial No. 621,567. Term of patent 3½ years.

To all whom it may concern:

Be it known that I, GEORGE R. STEINHAUSER, of the city of St. Louis and State of Missouri, have invented a new and original Design for Lamps, of which the following is a full, clear, and exact description, reference being had to the accompanying drawing, forming a part hereof.

The figure is a front elevation of a lamp embodying the features of my design.

The leading feature of my design for a lamp consists of a base resting upon feet, which feet project outwardly and downwardly from said base, a pillar projecting upwardly from said base, a disk-shaped body resting upon said pillar and having a clock-dial upon its front face, a pillar projecting upwardly from said disk-shaped body, a cylindrical body resting upon the last-mentioned pillar, said body being conical at its upper and lower ends, a pillar projecting upwardly from said cylindrical body, a cylindrical foraminous body projecting upwardly from said pillar, and a globe or chimney resting upon said foraminous body.

In the drawing, 1 is the base; 2, the disk-shaped body mounted upon the base and having the clock-dial on its front face; 3, the reservoir of the lamp; 4, the burner; 5, the globe, and 6 the chimney.

The base 1 rests upon the feet 7, which project outwardly and downwardly from said base, and the hemispherical projection 8 is seen between said feet 7 and approximately in vertical alinement with the center of the lamp. The surface 9 of the base is circular in plan and inclined or conical in elevation, being wider at its bottom than at its top, and upon said surface appears the ornamentation 10. Extending in a horizontal plane around the upper end of the base 1 is a bead 11, upon the face of which are formed hemispherical projections 12. The portion 13 of the base 1, which is above the ring 11, is conical and considerably smaller at its upper end than at its lower end, and the circular pillar 14 rests in a vertical position upon said conical portion

13, and said pillar 14 is surmounted by a bead 15.

The disk-shaped body 2 rests upon the pillar 14 above the bead 15, and has the clock-dial 16 upon its front face. The pillar 17 rests upon the disk-shaped body 2 in vertical alinement with the pillar 14, and the bead 18 extends around said pillar 17 immediately above the disk-shaped body 2 or upon the extreme lower end of said pillar 17. The bead 19 extends around the central portion of the pillar 17 and is somewhat larger than the bead 18, and the hemispherical projections 20 are formed upon the face of said bead 19.

The reservoir 3 is a cylindrical body, having an inverted-cone-shaped bottom 21, which rests upon the upper end of the pillar 17, and its upper end 22 is conical. Upon the surface 23 of the cone-shaped portion 21 of the reservoir appear the ornamental figures 24 and 25, and the beads 26 extend in a horizontal plane around said reservoir at the point of its largest diameter, said point being at the junction of the portion 21 with the portion 22. A bead 27 extends around the portion 22 of the reservoir in a position parallel with the beads 26 and a short distance above said beads 26, and the bead 28 extends around said portion 22 a short distance above the bead 27. At the apex of the portion 22 is a bead 29, upon which rests the circular pillar 30, and the bead 31 appears above the upper end of said pillar 30. Resting upon the bead 30 is a cylindrical foraminous body 32, surmounted by the beads 33, and the globe 5 rests upon said beads 33, and the upper end of the chimney 6 appears above the globe 5. Upon the globe appear the ornamental figures 34.

I claim—

The design for a lamp, as herein shown and described.

In testimony whereof I affix my signature in presence of two witnesses.

GEORGE R. STEINHAUSER.

Witnesses:

EDWARD E. LONGAN,
S. G. WELLS.
